UNITED STATES PATENT OFFICE.

CHARLES W. BRADFORD, OF THORNDIKE, MAINE.

KEY-FASTENER.

SPECIFICATION forming part of Letters Patent No. 336,768, dated February 23, 1886.

Application filed October 22, 1885. Serial No. 180,586. (No model.)

To all whom it may concern:

Be it known that I, CHARLES W. BRADFORD, of Thorndike, in the county of Waldo, State of Maine, have invented a certain new and useful Improvement in Key-Fasteners, of which the following is a description sufficiently full, clear, and exact to enable any person skilled in the art or science to which said invention appertains to make and use the same, reference being had to the accompanying drawings, forming part of this specification, in which—

Figure 1 is a front elevation representing my improved key-fastener detached from the key; Fig. 2, a like view representing it provided with the guard; Fig. 3, a front elevation representing the fastener attached to the key; Fig. 4, a top plan view of the guard, and Fig. 5 an isometrical perspective view representing the fastener in use to secure the key.

Like letters of reference indicate corresponding parts in the different figures of the drawings.

My invention relates to that class of key-fasteners which are designed to be suspended from the door-knob or spindle of the door-knob on the inside of the room, and adapted to engage and prevent it from being turned by burglars or others to unlock the door from the outside; and it consists in a novel construction and arrangement of the parts, as hereinafter more fully set forth and claimed, by which a more effective and otherwise desirable article of this character is produced than is now in ordinary use.

The nature and operation of the improvement will be readily understood by all conversant with such matters from the following explanation.

In the drawings, A represents the fastener proper; B, the guard; C, the key; D, the attaching chain; E, the key-ring, and H the door-knob.

The fastener proper is composed of a single piece of elastic wire, preferably steel, and is approximately A-shaped in front elevation, as shown in Figs. 1 and 3. Each leg m of the fastener is corrugated to produce the depressions x, and turned out slightly at the bottom 50 to form the hooks r.

The guard B consists of a flattened oblong shell, composed preferably of sheet metal and provided with an elongated slot or opening, f, in its top, and its object is to prevent the fastener from tearing or injuring the garment when it is carried in the pocket.

To attach the guard to the fastener, the legs m are compressed, the hooks r inserted in the slot f, and the legs permitted to expand, as shown in Fig. 2.

In Fig. 3 the fastener is represented as attached to the key C by the key-ring E and chain D, one leg, m, of the fastener being provided with an eye, z, formed integral therewith, for securing the chain to the fastener. I do not, however, confine myself to providing the fasteners with an eye for the chain or to locating said eye at one side of the fastener, as it may be disposed at the top or in any other suitable position. The hooks r and shield B 70 may also be omitted, if desired. Neither do I confine myself to attaching the fastener and key by means of a chain and key-ring or in any other manner, as the fastener may be used separately, if preferred.

In the use of my improvement, the door being locked and the key in the lock, the legs m of the fastener are passed astride the neck v of the knob H, after which they are compressed and inserted in the bow of the key C, 80 where they are permitted to expand and thereby fasten the key in a manner which will be readily obvious without a more explicit description.

When the legs of the fastener expand after 85 being inserted in the key, the bow of the key falls into two of the depressions x, thereby preventing it from being readily detached therefrom.

As the height of the knob H from the key-hole of the lock varies considerably according to the style or kind of lock used several depressions, x, are employed in each of the legs m to correspond therewith. I do not, however, confine myself to the use of several depressions in each of the legs, as one or more may be employed as desired.

Having thus explained my invention, what I claim is—

1. The key-fastener A, having the legs m, com- 100

posed of a single piece of elastic wire and provided with depressions α , for receiving the bow of the key, and hooks r , for engaging a guard, substantially as described.

5 2. The key-fastener A, composed of a single piece of elastic wire and provided with two or more depressions, α , for receiving the bow

of a key, and with the eye z , for attaching a chain, substantially as set forth.

CHARLES W. BRADFORD.
